H. A. KUHN.
CHAIN FOR MINING MACHINES.
APPLICATION FILED MAY 18, 1914.

Patented July 3, 1917.

UNITED STATES PATENT OFFICE.

HARRY A. KUHN, OF PITTSBURGH, PENNSYLVANIA.

CHAIN FOR MINING-MACHINES.

1,232,051.

Specification of Letters Patent.

Patented July 3, 1917.

Application filed May 18, 1914. Serial No. 839,336.

To all whom it may concern:

Be it known that I, HARRY A. KUHN, a citizen of the United States, and resident of Pittsburgh, in the county of Allegheny and 5 State of Pennsylvania, have invented a new and useful Improvement in Chains for Mining-Machines; and I do hereby declare the following to be a full, clear, and exact description thereof.

10 My invention relates to chains for mining or like machines where said chains are driven by sprocket wheels, and are mounted in guides, and where the flights carrying the cutters or dislodging devices are connected 15 at intervals to said chain and adapted to enter the mass of coal and dislodge the same.

The object of my invention is to make the bit on the end of a flight as effective as a cutting tool as if the bit were a part of a 20 chain traveling in tension and to provide for the relieving of the strain on these flights and for the holding of the links in alignment, so that the links are held from bearing against the chain guides and creating 25 friction which retards the movement of the chain and increases the power required to drive the same.

In the accompanying drawing, Figure 1 is a plan view of a portion of a chain showing 30 my improved chain arranged therein; Fig. 2 is an outside edge view partly in section; Fig. 3 is a section on the line 3-3, Fig. 1; Fig. 4 is a section on the line 4-4 Fig. 2, and Fig. 5 is a modified form of my 35 invention.

In the drawing, the numeral 2 designates a suitable chain guide which is made up of 40 suitable rolled sections and comprises the bottom plate 3, the channel member 4 and the angle member 5. The angle-member 5 is supported on the channel member 4 and has the downwardly extending flange 6 which leaves the opening 7 for entrance to the space 8 containing the chain 9. The 45 chain 9 is made up of links in the usual manner connected by the bolts 10. The lower links 11 are thicker than the upper links 12 and said lower links are adapted to rest on the bottom plate 3 of the chain guide. The 50 lower links 11 have the lugs 13 which project out through the opening 7 and pivotally secured to said lugs by the bolts 14 are the flights 15. The flights 15 have the arms 16 which carry the idle rollers 17 which bear 55 against the flange 6 of the angle member 5. The idle rollers 17 are held within the bifurcated end portion 18 of the arm 16 and the lower portion of said bifurcated end has the projection 19 which extends within the opening 7 and is adapted to bear against the 60 lower link 11 of the chain and preferably at the pivotal point of said link. The said link 11 at this point has the flat face 20 with which the projection 19 engages.

The flights 15 are provided with the cutters 21 which are secured thereto by bolts 22, or if desired, said cutters may be formed integral with the flights. The flights 15 form part of a conveyer mechanism in connection with a mining-machine such as set 70 forth and claimed in an application of mine of even date herewith, Serial No. 839,325, and said flights move over the pan 23. Where the chain is employed in connection with the dislodging and conveying away of 75 coal which has been undercut, and then separated along its lines of cleavage, so as to drop into the undercut, the said chain is advanced into the coal and the flights with the cutters 21 pass in under the coal 80 and the coal is dislodged, and, by the movement of the flights 15, is moved along the pan 23 to be conveyed back to the pit-car in the rear of the machine, all as clearly set forth in the above application. As the 85 flights enter the coal, the strain will tend to force the flights backwardly and by having the arms 16 which engage the chain guide, I obtain a greater leverage and there is a corresponding reduction of the strain on the 90 flights as well as on the chain carrying the same. Where the flights are moving on the straight portion of the chain-guide, the projections 19 engage the links 11 and prevent the chain from buckling or kinking, and 95 the links of the chain are held from moving in frictional contact with the inner face of the flange 6, thereby reducing the friction and the power required to drive the chain. The arms 16 are slightly curved so as to 100 conform substantially to the curve of the chain guide. In Fig. 5, I have illustrated a modified form of my invention in which the arm 16^a projects rearwardly sufficiently to engage the succeeding flight carrying link 105 at a point between the pivots. The projection 19^a engages a shoulder 20^a on the link 21^a. By engaging the link between the pivots there is no opportunity for the buckling 110 of the chain.

What I claim is:

1. In a mining-machine, the combination

of a chain-guide, a chain therein, flights pivotally connected to said chain, and rearwardly extending arms on said flights engaging said chain-guide and said chain at 5 points between the chain-link pivots of the following link.

2. In a mining-machine, the combination of a chain-guide, a chain therein, flights pivotally connected to said chain, rearwardly extending arms on said flights engaging said chain-guide, a projection on said arm entering the chain-guide and engaging said chain. 10

3. In a mining-machine, the combination of a chain-guide, a chain therein, flights pivotally connected to said chain, inwardly extending arms in said flights engaging said chain-guide, a projection on said arm enter- 15

ing said chain-guide, and engaging the lower links of said chain.

4. In a mining-machine, the combination of a chain-guide, a chain therein, links on said chain having lugs projecting out from said chain-guides, flights pivotally connected to said lugs, rearwardly extending arms on said flights engaging the chain-guide and projections on said arms engaging the links on said chain at a point between the pivots of the link succeeding flight-carrying link. 25

In testimony whereof, I the said HARRY A. KUHN have hereunto set my hand. 30

HARRY A. KUHN.
